(57) **CLAIM**

The ornamental design for a portion of an audio component, as shown and described.

DESCRIPTION

FIG. 1 is a perspective view of a portion of an audio component showing my new design;

FIG. 2 is a top plan view thereof;

FIG. 3 is an elevational view thereof;

FIG. 4 is an end elevational view thereof;

FIG. 5 is a top plan view of a mirror image version of the portion of an audio component shown in FIG. 2;

FIG. 6 is a top plan view of the portion of an audio component as shown in FIG. 2, but shown in a different orientation on the audio component; and,

FIG. 7 is a top plan view of a mirror image version as shown in FIG. 5, but shown in a different orientation on the audio component.

The broken line showing of the remainder of the audio component in all of the figures is for illustrative purposes only and forms no part of the claimed invention.
